George A. Turner

BY

Ring. W. D. Webster

ATTORNEY

UNITED STATES PATENT OFFICE.

GEORGE A. TURNER, OF STOCKTON, CALIFORNIA.

INDUCTANCE-COIL FRAME.

Application filed September 28, 1925. Serial No. 59,007.

This invention relates to improvements in the structure of inductance coils of all kinds, with particular reference to that type used in connection with radio receiving and sending apparatus. This invention relates specifically to the coil frame upon which the wires of the coil are wound.

The object of the invention is to produce a coil frame of simple, inexpensive and easily assembled structure and one in connection with which there will be a low current loss due to the fact that the contact of the coil wires with the frame will be minimized to a very great degree over coil constructions where the wires are wound on a core or frame of the well known cylindrical or hard rubber types.

In addition to these objects a further object is to provide such a construction as will be extremely rigid and compact and render the coil highly efficient in operation.

These objects I accomplish by means of such structure and relative arrangement of parts as will fully appear by a perusal of the following specification and claims.

In the drawings similar characters of reference indicate corresponding parts in the several views:

Fig. 1 is a perspective view of the new coil frame showing the winding thereon, where in the frame is made of two continuous bakelite plates arranged and constructed as will later appear.

Fig. 2 is a similar perspective view showing a modification of the structure shown in Fig. 1 in that the supports for the winding are made of bakelite strips suitably set into end clamps.

Fig. 3 is an end section of still another modified form of frame showing how my improved construction can be utilized in making a coil having a double winding.

Referring now more particularly to the characters of reference on the drawings, and with particular reference to the construction shown in Fig. 1, the winding frame in this instance consists of two continuous bakelite plates or panels 1 mortised together at right angles at their median lines as at 2. The coil wire 3 is then wound around the spaced edges of the plates 1 and provided with suitable terminals 4 and 5 set into the plates 1 at desired points.

It will be seen that the wire can be very

tightly wound around the frame and the 55 tighter it is wound the more rigid and compact the coil will be and less apt to have the coil wire become disarranged and shorted than in other types of coils.

Furthermore by having the wire 3 contact 60 only with the free edges of the plates 1 this minimizes the contact of the wire with any surface and results in the fact that the coil will have a low current loss when in use. The cheapness of materials and of assembly 65 will be obvious, and also the manufacturing cost will be very little, since in production the coil can be put together and wound with very slight effort.

In the type of coil shown in Fig. 2, in 70 place of the continuous bakelite plates 1 I provide narrow bakelite strips 6 which are set into end clamps consisting of supporting arms 7 having strip clamps or ears 8 at their extremities. The strips of bakelite 6 75 are set into the strip clamps and fixed rigidly in connection therewith by small countersinks 9 driven into corresponding depressions in the bakelite strips,

In this construction the end clamps would 80 be made out of sheet metal and cut and shaped into position by pressing, and brackets 10 would be struck out at the center of the clamps for fastening the coil in position for operation.

The wire 11 would be wound around the strips 6 the same as shown for the wire 3 around the continuous plates, as in Fig. 1, the advantages being the same.

In this type of structure shown in Fig. 2, 90 however, the cost of the coils would be very much less than in the type shown in Fig. 1, since the bakelite is the most expensive part of the structure and by using the strips instead of the plates the cost of material would 95 be much reduced.

In Fig. 3 I have shown a similar end clamp construction to that shown in Fig. 2 showing how the same could be adapted for use when a double winding of the coil is 100 desired.

When the coil is made with a double winding instead of the single bakelite strip 6 I would first put in a set of bakelite strips 12 which would project only part way of 105 the length of the strip clamps 13 and the first winding 14 would be wound therearound. A second set of bakelite strips 15

would then be pressed into the strip clamps, and the second winding 16 would then be wound therearound. The two windings would be subject to the same advantages 5 claimed in connection with the invention, and at the same time they would be rigidly and compactly held and separated and insulated from each other.

From the foregoing description it will be 10 readily seen that I have produced such a device as substantially fulfills the objects of the invention as set forth herein.

While this specification sets forth in detail the present and preferred construction 15 of the device, still in practice such deviations from such detail may be resorted to as do not form a departure from the spirit of the invention, as defined by the appended claims.

20 Having thus described my invention what

I claim as new and useful and desire to secure by Letters Patent is:

1. A coil frame comprising end spiders each having a plurality of arms radiating from a common center, transversely spaced 25 and parallel ears turned inwardly from the outer ends of the arms, and rigid strips of insulation material, to form supports for a coil winding and to connect the spiders, fitted between the ears and extending between the arms of the two spiders.

2. A coil frame comprising end spiders, winding supporting elements extending between the spiders at spaced intervals, and brackets for supporting the frame in a suspended position struck outwardly from the spiders centrally thereof.

In testimony whereof I affix my signature.

GEORGE A. TURNER.
